UNITED STATES PATENT OFFICE.

JAMES BROOKS, OF MOUNT VERNON, NEW YORK, ASSIGNOR TO MATTHEW HAWE, OF PELHAM MANOR, NEW YORK.

SPARK-PLUG.

1,340,116.

Specification of Letters Patent. Patented May 11, 1920.

Application filed September 29, 1919. Serial No. 327,227.

To all whom it may concern:

Be it known that, I, JAMES BROOKS, a citizen of the United States of America, residing at Mount Vernon, New York, have 5 invented a new and useful Spark-Plug, of which the following is a specification.

My invention relates to a so-called spark plug for use in internal combustion engines. The object is to provide a construction which facilitates the rapid and economical production thereof, and which affords 10 in the finished article great durability.

In the accompanying drawing, the single figure is a vertical sectional view of the 15 complete plug.

1 represents the shell or main body which has a central unthreaded passage therethrough. The lower part of said passage is counterbored to form a shoulder 2. The 20 lower part of the shell is provided with the usual external thread 3, while the upper part is preferably provided with a hexagonal head to receive a wrench. 5 is a contact point at the inner end of the shell 1. 25 The shell 1 is easily and quickly produced by a very simple machining operation and requires only one threading operation. 6 is a central pin, the inner end of which constitutes the second contact point and 30 which as shown, may be bent so as to lie close to the contact point 5, the space between the two being adjustable in the usual manner so as to afford the proper gap across which the spark has to jump. 7 35 is a shoulder near the inner end of the pin. 8 is a sleeve of insulating material located around the middle portion of the pin 6 and against the shoulder 7, said insulation being of any suitable material such 40 as mica. 9 is a sleeve of any suitable material such as iron or steel which is fixed tightly on the insulating sleeve 8 so as to permanently bind the same in place. The sleeve 9 also forms a holding shoulder 10 45 and centers the core in the shell. When the parts are assembled, the external diameter of the sleeve 9 makes an easy sliding fit within the lower end of the counterbored portion of the shell 1. 11 is a packing 50 washer between the shoulders 2 and 10. 12 is a block of insulating material having a central passage arranged to slide over the outer end of the pin 6 and to stand over the adjacent portion of the in-

sulating material 8 which surrounds said pin. 14 is a nut which is threaded on the outer end of the pin 6 to hold the insulating block 12 firmly against the outer end of the shell 1 and which at the same time serves to draw the shoulder 10 and washer 11 tightly against the shoulder 2. 15 is a lock nut for the nut 14. 16 is the usual binding-post thumb nut which is arranged to hold the end of a conducting wire in electrical engagement with the pin 6. 17 is a packing washer which may be provided if desired between the upper face of the shell 1 and the lower face of the block 12. The block 12 is preferably made of a material capable of resisting fracture, for example, a compressed asbestos compound, or it may be made of a heavy piece of porcelain-like material; however, I prefer to use the former material since it will resist severe usage. It will be noted that the removable core, comprising the central pin, the insulating sleeve 8, and the metallic sleeve 9, is loaded into the shell from the inner or lower end instead of from the outer end, which latter practice is the customary one. This new method of assembly is not only simple but it also avoids the necessity of providing any internal threading of the shell thereby greatly cheapening the manufacturing cost. If desired the binding 85 sleeve 9 may have a slight internal taper so as to further resist any tendency to slip, or slide on the insulating sleeve 8 when drawn into place by nut 14.

I claim:

A spark plug comprising a metallic shell having a longitudinal counterbored passage therethrough forming an internal shoulder the inner bore of said passage being larger than the outer bore, a thread on the outer side of the inner end of said shell, a removable core comprising a metallic pin having a fixed metallic shoulder near its inner end and threaded at its outer end, an insulating sleeve surrounding the middle portion of said pin and bearing against said shoulder, a metallic centering sleeve surrounding said insulating sleeve intermediate the length thereof and fixedly mounted thereon against independent longitudinal movement, that part of the insulating sleeve between said centering sleeve and the threaded portion of the pin being of greater

length than the smaller portion of the counterbore in the shell so as to project above the outer end of said shell, a separate insulating piece mounted on the outer end of the shell and surrounding that part of the insulating sleeve which projects above the shell, and a clamping nut mounted on

the threaded part of said pin and bearing against said insulating piece and operating to draw said centering sleeve toward said stop shoulder within the shell to hold said parts rigidly assembled. 10

JAMES BROOKS.
